UNITED STATES PATENT OFFICE.

SAMUEL R. BOYER, OF CLEVELAND, OHIO.

MILLING-MACHINE.

SPECIFICATION forming part of Letters Patent No. 726,248, dated April 28, 1903.

Application filed May 28, 1902. Serial No. 109,373. (No model.)

To all whom it may concern:

Be it known that I, SAMUEL R. BOYER, a citizen of the United States, residing at Cleveland, in the county of Cuyahoga and State of Ohio, have invented certain new and useful Improvements in Milling - Machines, of which the following is a specification.

My invention relates to cutting attachments for milling-machines, and has for one of its objects to provide a device of the character described that is adapted to be attached to milling-machines now in use and that has means to simultaneously drive several cutters, said cutters being removable and replaceable in their spindles, which are in turn mounted in a revoluble turret that may be turned so that the plane containing the spindle-axes may approach or recede from the horizontal, and thereby accomplish the principal object of my invention—viz., the provision of a machine for cutting a predetermined configuration on the work-piece and finishing the work in one passage through the machine instead of several operations, as is necessary in machines in common use. By this structure the cost of milling a work-piece such as that shown at D in Figure 1 is appreciably reduced as well as the uniformity of the output assured, because one setting of the machine is all that is necessary, while in machines in which only a portion of the work is done at a time the resetting of the machine that is necessary not only consumes valuable time, but variation of the output is difficult to avoid except when the work-pieces are exactly alike.

Another feature of my invention is the providing of a dust and dirt proof casing for the driving mechanism, which may be readily opened to permit the gearing to be exposed.

My invention also permits the gear-wheels to be readily removed for the purpose of changing the relative speed of the cutters.

Another object of my invention is to so construct the spindles carrying the cutters and other parts subject to friction as to provide for their wear and at the same time keep the various parts in the desired alinement.

Additional advantages of my invention will appear hereinafter and by reference to the accompanying drawings, in which—

Fig. 1 is a view of a portion of a milling-machine, showing my invention in place

thereon; Fig. 2, a front view of the device; Fig. 3, a side view; Fig. 4, a vertical section taken through the cutter-spindles, and Fig. 5 a detail of the driving-arbor.

Referring to the drawings, in which similar reference-characters indicate corresponding parts throughout the several views, a represents a milling-machine of any desired construction having the overhang-arm B and the driven spindle C.

My invention is adapted to be attached to the milling-machine A by means of a bracket 1, having its upper part formed with a loop 2, which is secured to the overhang-arm B by means of screw-bolts 3. The lower part of the bracket is formed with a semicircular recess, and a removable segment 4 is bolted to said bracket to receive the swivel housing or turret 5, said turret being revoluble in said bracket and adjusted by means of a worm-gear 6, cut into its periphery, meshing with a worm 7, the shaft of which is journaled in a bracket 8, swivelly mounted on the bracket 1 by means of set-screw 9. The object of swivelly mounting the worm-shaft is to permit a rapid revolution of the turret 5 by throwing the worm 7 out of gear with the worm-gear 6 and then by throwing the worm into engagement with the worm-gear secure a fine adjustment, 10 representing a gage on the edge of the turret, and 11 a point on the bracket 1, while 12 is a gage on the worm-shaft for minute adjustment, 13 being a point on the bracket 8.

The front of the turret 5 is formed with a depression 14 and three screw-threaded bores 15 opening therein, the bores being to receive the spindles 16 for driving the cutters 16^a, the shanks thereof being driven into the taper-bores 17 in said spindles, 18 being a straight bore communicating with the taper-bore to permit the insertion of an instrument behind the cutter-shank when it is desired to drive it out. The spindle 16 is formed with a shoulder 19, a tapering portion 19^a, and a reduced and screw-threaded end 20, over which an adjusting-nut 21 is placed, the nut 21 being screw-threaded to fit the screw-threaded bore 15 and having a straight bore tapering outwardly at its end to fit the rear of the spindle 16.

22 is a check-nut on the adjusting-nut 21, 105 and 23 a nut on the screw-threaded end of

the spindle 20 to compensate the wear of the shoulder 19 and tapering bore in the adjusting-nut 21.

The central spindle is formed with a taper-bore 24 at its rear and a key-slot 25 to receive the key 26 on the driving-arbor 27, which is inserted in the bore of the driven spindle C, 28 being a taper-plug adapted to seat in the taper-bore 24 to insure alinement of the cutter-spindle 16 and the driven spindle C.

29 is a screw-threaded cap to firmly secure the driving-shank 27 to the cutter-spindle 16 and fitting the screw-threaded end 20 thereof.

30 represents meshing gear-wheels inserted over the spindles 16 and turning said spindles by means of semicircular keys 31, sunk into said spindles and engaging splines 32 in the gear-wheels. The depression 14 is covered by a plate 33, which is secured to the 20 turret 5 by means of set-screws 34, said plate 33 being provided with three holes 35, which are screw-threaded to secure adjusting-rings 36, having taper-holes to fit the cone-shaped hubs of the gear-wheels 30. It will be understood from this construction that the plate 33 may be removed from the turret 5, exposing the gear-wheels 30, and the gear-wheels may be changed so as to provide for any desired relative speed of the spindles 16 by sliding said gear-wheels off the end of the spindles and out of engagement with the keys 31 and installing other gear-wheels having the proper size to secure the relative speed of the spindles that may be necessary to perform 35 the work in hand.

The operation of my invention will readily appear by inspection of the accompanying drawings. The work-piece is fed to the cutters in a horizontal direction, the cutters operating on the side of the work-piece. In Fig. 1 will be seen a work-piece D in position, being held to a horizontally-slidable table E by means of a clamp F, secured by a bolt G.

It will be readily seen that among the advantages of my machine is the dispensing with a number of formed cutters in duplicate work, as various outlines can be cut by simply altering the adjustment of the turret. By having the spindles set on a horizontal line 45 the cutters necessary to rough and finish the work may be mounted in the spindles and the work completed by putting the material through the machine but once. Another advantage is in the fact that the diminishing of 50 the size of the cutters in grinding may be compensated by adjusting the turret.

Having thus described my invention, what I claim is—

1. The combination with the overhang-arm 60 of a milling-machine, of a bracket mounted thereon, a turret revolvably mounted in said bracket, cutter-spindles journaled in said turret, and means to cause a simultaneous rotation of the cutter-spindles, substantially 65 as shown and described.

2. The combination with the overhang-arm of a milling-machine, of a bracket mounted

thereon, a turret revolvably mounted in said bracket, cutter-spindles journaled in said turret, means to cause a simultaneous rotation of the cutter-spindles, and means to longitudinally adjust said cutter-spindles, substantially as shown and described. 70

3. The combination with the overhang-arm of a milling-machine, of a bracket mounted 75 thereon, a turret revolvably mounted in said bracket, cutter-spindles journaled in said turret, means to connect one of said cutter-spindles with the driven spindle of the machine, meshing gear-wheels removably keyed 80 to said cutter-spindles, and means to longitudinally adjust each individual cutting-spindle, substantially as shown and described.

4. The combination with the overhang-arm of a milling-machine, of a bracket mounted 85 thereon, a turret revolvably mounted in said bracket, cutter-spindles journaled in said turret, one of said cutter-spindles connected to the driven spindle of the machine by means of a clutch, meshing gear-wheels removably 90 keyed to said cutter-spindles, and means to longitudinally adjust each individual cutting-spindle, substantially as shown and described.

5. The combination with the overhang-arm of a milling-machine, of a turret suspended 95 therefrom having screw-threaded bores, adjusting-nuts inserted in said screw-threaded bores, cutter-spindles journaled in said adjusting-nuts, and means to cause a simultaneous rotation of said spindles, substantially 100 as shown and described.

6. The combination with the overhang-arm of a milling-machine, of a turret suspended therefrom having a recess in its face, cutter-spindles journaled in bores formed in said 105 turret, gear-wheels mounted on said spindles by means of keys and splines and seating in said recess, and a face-plate to cover said recess and gearing, substantially as shown and described. 110

7. The combination with the overhang-arm of a milling-machine, of a turret suspended therefrom having a recess in its face and screw-threaded bores, cutter-spindles having an enlarged and tapering shoulder and a reduced and screw-threaded rear end, adjusting-nuts formed with a bore to fit said tapering shoulders and reduced rear ends and screwed into said screw-threaded bores, check-nuts mounted on said adjusting-nuts, nuts 115 mounted on the screw-threaded ends of the spindles, gear-wheels having cone-shaped hubs mounted on said spindles by means of keys and splines and seating in the recess in said plate, a face-plate having screw-threaded bores to receive said spindles, and rings having tapering bores to fit said cone-shaped hubs, substantially as shown and described. 120

In testimony whereof I hereto affix my signature in the presence of two witnesses.

SAMUEL R. BOYER.
